UNITED STATES PATENT OFFICE.

OSCAR JOHAN CHRISTIAN RIIS, OF COPENHAGEN, DENMARK.

FILE FOR RECEIVING LOOSE SHEETS, MAGAZINES, AND THE LIKE.

Application filed November 29, 1924, Serial No. 752,902, and in Denmark September 9, 1924.

This invention relates to a file for inserting loose sheets, magazines, sheets of music, newspapers and the like, a file of the kind that has the inside of its back, at the top and 5 at the bottom, fitted with holding devices, between which there is passed a zigzag string or the like, which serves the purpose of attaching the various sheets or the like to the file. All such files, however, have the 10 disadvantage that it is difficult to insert the loose sheets or the like where they belong, because the string on which the sheets are to be inserted is attached to the back of the file, both at the top and at the bottom.

15 The present invention consists therein that only one end of the said string is attached to the file, so that the said string can be passed over the holding members at the top and at the bottom on the inside of the back 20 of the file, accordingly as the file is filled with sheets and the like, besides which in connection with the file there is an arrangement for attaching the free end of the string. The advantage of this is that it is now possible 25 to bring a sheet or the like into place in the file, and then to attach it to the back of said file by inserting the said string into the sheet, and then passing it over one of the holding devices at the top or at the bottom 30 of the back, before the string is finally attached to the file.

Moreover it is a distinguishing feature of this invention that the said holding devices, which serve the purpose of keeping the 35 string in place, are attached to two metal channel bars of such a shape that, directly from the end of the file, they can be pushed over the back of the said file, round which they are then pressed together. The tension 40 of the strings will then keep the metal bars in position without special means being required. As the two sides and the back of the file can be made of a single piece of millboard or the like, an exceedingly cheap and 45 convenient make of such a file may be attained.

A constructional form of the invention is shown in the accompanying drawing in which—

- 50 Fig. 1 is a file which is opened; and
 Fig. 2 is a longitudinal section through one end of the back of the file.
- The file consists of a back *a* with two sides *b* and *c*, which together with the back *a* may 55 be made of a single piece of millboard or the like. On the juncture between the back and

the side-parts a crease *d* is pressed into the cover, so that the sides can easily be turned relatively to the back *a*.

To the top of the back *a* is secured a number of hooks *e*, *e*, . . . and at the bottom on the back *a* there is secured a corresponding number of hooks *f*, *f*, . . . By means of a rivet *g* or the like a disc *h* of millboard or the like is attached to the rear side *c* of the cover.

A string *k* has at one end an eye or a loop *l* by which it is hooked on to the hook *e*, and then it is passed over the hook *f* and back over the hook *e*. As shown on the drawing it may then be passed over the hook *e*, which is the rearmost of the hooks *e*; finally it is fixed below the disc *h* by being pressed in between the said disc and the side-part *c*. The free surplus end of the string *k* may be 75 twisted around a card *m* hanging from the disc *h* and may be unwound therefrom as the file is filled more and more. In order to prevent the card *m* from unwinding, the free end of the string may be left hanging from 80 the card, so that it can be pressed below the disc *h* together with the part of the string lying between the hook *e* and the card *m*.

When sheets are to be inserted into the file shown, the string *k* is freed from the disc *h* and from those hooks *e* and *f* over which it is passed, with the exception of the hook *e*. The first sheet is now brought into place in the file below the hook *e*, and the string *k* is inserted into the sheet, whereafter it is 90 passed over the hook *f*. If no more sheets are to be inserted into the file, the string *k* may now be passed over the hook *e*, and then over the hook *e*, and finally be fixed below the disc *h*. It is also possible, however, 95 to pass the string directly from the hook *f* to the hook *e*, and then to fasten it beneath the disc *h*.

As shown in Fig. 2 the hooks *e* are made in one piece with a channel bar *n*, which from the end is pushed over the back of the file. The bar with the hooks on it is stamped out of plate and bent into the form shown in Fig. 2. The channel bars *n* protect the ends of the back from wear and give the necessary stiffness to the back in a transverse direction. Moreover, the said bars give a handsome and strong appearance to the back of the file when seen from behind. The sides *b* and *c* of the file, which parts, when the file is shut, are at right angles to the back *a*, are 110 conducive towards giving the necessary stiff-

ness to the said back in a longitudinal direction.

The file described can be made in different sizes according to the size and the quantity of the sheets it is intended for. One of the advantages of this invention is that it is possible, without procuring particular tools, to make files of any dimensions, as the back and the side parts are made simply by cutting out millboard or the like, and the difference, as far as the channel bars are concerned, only consists in the varying length of the said bars.

The constructional form of the invention shown in the drawing may be varied in many ways, and it may here be mentioned that the construction of the holding devices *e* and *f* and also of the disc *h*, in each individual case, may be varied according to the demands put to the file. The disc *h* may be arranged at any point of the file. Instead of using the above mentioned arrangement to prevent the card *m* from unwinding by pressing the free end of the string below the disc *h*, any other suitable arrangements may be used; for instance, as it is customary with other cards, it is possible to employ a slit *o* disposed in connection with the card, into which slit the string may be engaged.

I claim:

1. A file for receiving loose sheets, magazines and the like, on the inside back of which both at top and bottom are disposed

channel bars, the length of these bars being equal to the breadth of the back and the space between the flanges thereof equal to the thickness of said back, said bars provided with hooks, a string adapted to retain the papers placed into the file, attached at one end to the one of said bars and arranged in a zigzag line between the hooks of said top and bottom bars, respectively and a disc or the like attached to the rear cover of said file and adapted to have the free end of said string engaged between it and the rear cover.

2. A file for receiving loose sheets, magazines and the like, on the inside back of which both at top and bottom are disposed channel bars, the length of these bars being equal to the breadth of the back and the space between the flanges thereof equal to the thickness of said back, said bars provided with hooks, made in one piece with said bars by stamping out the one flange and being bent off therefrom, a string adapted to retain the papers placed into the file, attached at one end to the one of said bars and arranged in a zigzag line between the hooks of said top and bottom bars, respectively, and a disc or the like attached to the rear cover of said file and adapted to have the free end of said string engaged between it and the rear cover.

In witness whereof I affix my signature.
OSCAR JOHAN CHRISTIAN RIIS.
